UNITED STATES PATENT OFFICE.

GEORGE STEEL, OF BROOKLYN, NEW YORK, ASSIGNOR TO HENRY MADDOCK, OF SAME PLACE.

DESIGN FOR A DISH.

SPECIFICATION forming part of Design No. 20,374, dated December 9, 1890.

Application filed March 24, 1890. Serial No. 345,164. Term of patent 7 years.

To all whom it may concern:

Be it known that I, GEORGE STEEL, a citizen of the United States, residing in Brooklyn, in the county of Kings and State of New York, have invented and produced a new and original Design for Covered Dishes, of which the following is a specification.

The present design consists in the shape and surface ornamentation of the body and cover of dishes and of the handles for the body and cover.

The design is applicable to various dishes constituting what is known as a "dinner-set" or other set of dishes, as well as a soup-tureen, vegetable-dish, sugar-bowl, &c.

The accompanying photograph shows the design applied to a low dish of the character of a soup-tureen or vegetable-dish.

Figure 1 is a perspective view looking from above. Fig. 2 is a similar view from another position, and Fig. 3 is a perspective view looking from beneath.

The body A of the dish is formed with oblique sides and ends, which are made slightly curved, the portion a, which is above the foot b, being slightly convex, and the portion c above being slightly concave and terminating in an upper rim d, which is directed upwardly. The outline of the body is diversified by slight corrugations extending from the foot upwardly to the rim. At the corners, which are rounded, several of these corrugations are grouped, as clearly shown at e e, forming a fluted corner, the flutes radiating slightly as they ascend. In the middle of each end of the dish is a line f, formed as a slight salient rib. Between this rib and the corner corrugations e the side and end surfaces of the dish are formed in horizontal planes with very slight reverse curves, the sides being slightly concave on each side of the ribs f and slightly convex adjacent to the nearest corrugation e. The rim d is correspondingly varied in outline, being indented at the junctions of the corrugations e e, as shown at i i, and being slightly salient at the junction of the rib f, as shown at j. The foot b is correspondingly varied, having indentations i' at the corners and being slightly recessed or indented at j' at the base of the rib f.

On each end of the dish is a handle B, hav-

ing the shape of a curved bar, terminating at one end in a leaf k, which lies flat against the exterior of the end of the dish. The bar curves in a graceful loop over the rim of the end of the dish, and its other end terminates in a knob l, which lies on the upper and inner side of the dish. The loop of the leaf is prolonged over the lower side of the bar, and the upper side thereof is formed with serrated or small leaf-like protuberances m.

The cover C is formed with a flat central portion or panel n, the outline of which is generally quadrilateral, varied, however, by being rounded at the corners and concaved on each side and end between the corners and the middle, the concave outlines joining at the middle to form a slightly-salient angle. The outer portions of the cover descend in graceful reverse curves to the lower edge or rim thereof, the shape being in general similar to the shape of the sides of the dish. The surface of the cover descends with a slight concave c' adjacent to the flat center, merging into the convex or dome-shaped portion a', below which the latter extends to and terminates at the rim of the cover. The corners are rounded and diversified by radial flutes or corrugations e' e', extending from the corners of the center n to the rim. Down the middle of each side and end extends a slightly-salient rib f'. The surface of the cover between this rib and the corner corrugations is formed slightly concaved adjacent to the rib on each side thereof and slightly convex adjacent to the corner corrugations.

The cover-handle D has the general form of an arch or loop, the ends of which rest on the flat center n of the cover. These ends have in general the form of leaves, the arched portion of the handle consisting of the stems of these leaves k', each of which terminates in a slight scroll-like knob l', the two knobs being arranged on opposite sides of the loop of the handle, near the middle thereof, giving the handle the appearance clearly shown in Fig. 1.

The handles B and D constitute segregable parts of my design, which may be used on other dishes and covers. My design is not necessarily restricted to a covered dish, since the cover may be removed or omitted, leav-

2
ing the remaining portion of the design for the body of the dish.

I have not deemed it necessary to illustrate all the different dishes of a set of dishes to which my design is applicable, the modification of a design in mere matters of proportion to adapt it from an elongated to a square dish or from a low to a high dish being well understood in the art.

10. What I claim is—

1. The design for the shape and surface ornamentation of a covered dish, substantially as shown in the accompanying photograph.

2. The design for the body of a dish, consisting of the shape and surface ornamentation thereof, substantially as shown and described.

3. The design for the cover of a dish, consisting of the shape and surface ornamentation thereof, substantially as shown and described.

4. In a design for a dish, the end handles B B thereof, substantially as shown and described.

5. In a design for the cover of a dish, the handle D thereof, substantially as shown and described.

In witness whereof I have hereunto signed my name in the presence of two subscribing witnesses.

GEORGE STEEL.

Witnesses:

GEORGE H. FRASER,
FRED WHITE.
